UNITED STATES PATENT OFFICE

2,028,429

RADIO RECEIVING DEVICE WITH DISTANT CONTROL

Edward F. Andrews, Evanston, Ill., assignor to
The Andrews-Hammond Corp., Chicago, Ill., a
corporation of Illinois

Application March 20, 1928, Serial No. 263,005

18 Claims. (Cl. 250—14)

My invention relates to a radio receiving apparatus and particularly to a radio receiving apparatus in which the power devices are separated from the radio frequency tuning means which are positioned in a portable container fully transportable about a room or about a house. In my device as herein shown the radio frequency amplifier and detector and tuning means of a radio set are positioned preferably in a small stand or container. For example the radio set proper may be located in an enlarged base which may rest upon the floor, and the control means for adjusting frequency and volume and for stopping and starting actuation of the set are located in the upper portion of the stand, preferably at such a height above the floor as to be convenient for a seated, standing or reclining operator. In the form herein shown a stem or tube projects upwardly from the enlarged base and at the upper end of the tube are positioned the control means and, if desired, a handle for moving the portable unit about. The stand and the radio set parts therewithin are connected by a multi-conductor cable to a fixed or semi-portable housing containing, for example, the audio amplifier and the power supply device for operating the complete radio set, including that portion of it located in the portable container. The portable stand or container may be carried from place to place within a range determined by the location of the fixed container or power box and the length of the cable connecting the power box to the stand. The distribution of the parts of the set between the two containers may be somewhat varied but I show herein the antenna and ground system as connected to the fixed or semi-portable container or power box, with the leads run to the radio frequency end of the set located in the stand through the flexible conductive connection. I have determined by practical test and operation that no serious interference occurs from running the various leads and the power source connections in the same cable. This is particularly true if the ground connection is made in the form of a braided wire sheath and the detector lead run inside of the sheath. The cable is not particularly sensitive to body capacity or proximity to metal objects, and the operation of the radio and audio frequency amplifiers of the set is entirely satisfactory. But in many cases it is preferable to shield some of the connections, as below set forth. This particular construction is of great advantage, especially where the audio

frequency amplifier, power devices, and loud speaker are of such a heavy or bulky nature as not to allow them to be practically portable as a unit.

It is a great advantage to have a small, convenient, portable and easily handled floor unit, which can be located, at the will of the operator, near any chair or couch which he may wish to occupy, to permit tuning without the necessity of arising. A floor stand of the type herein shown lends itself particularly readily to a decorative simplicity of design and can be made decorative without housing it in an expensive, obtrusive, heavy and space occupying piece of furniture. The power box in many cases, need not be decorative at all, and can be located at any inconspicuous space, or even in a closet, unless, as in some forms herein shown, the loud speaker is associated with it.

My improved type of radio receiver constitutes a highly advantageous way of constructing a readily portable radio set, particularly where the parts are too heavy or bulky to be placed in a single container as in my co-pending application Serial No. 263,007, Patent No. 1,922,008, August 8, 1933, or where it is desired to have a loud speaker located at some distance from the controls of the set, and still have the control portable. However, the loud speaker may be associated with either unit.

Further objects will appear from time to time in the course of the specification and claims.

I illustrate my invention more or less diagrammatically in the accompanying drawings, wherein—

Figure 1 is a perspective view of a form of my device;

Figures 2 and 3, taken together, illustrate a vertical section of the portable unit shown at the left of Figure 1; and

Figures 4 and 5, taken together, illustrate the wiring diagram of the two units, Figure 4 being the diagram for the portable unit and Figure 5 for the fixed or semi-portable unit or power box.

Like parts are indicated by like characters throughout the specification and drawings.

Referring to the drawings, A indicates a base or floor contacting member and A¹ a plate positioned upon and spaced above the base A, for example by the vertical supports A². Mounted in the space between the plate and the base and between the vertical supports, and supported on the plate, are a gang of three condensers, generally indicated as A³, each including the usual rotor and stator plates. The rotor plates are

mounted upon a vertical shaft A⁴ which passes through the plate A¹ and is secured against vertical movement in relation to said plate, for example by the upper bearing member or flange 5 A⁵ and a corresponding bearing member at the lower end of the shaft, not shown.

Secured to the plate A¹ is a plate B, to which is secured the collar B¹ which engages and secures the flanged end B³ of the vertical tube B².

10 C C indicate the usual type of tube sockets and C¹ C¹ shielded inductances of the usual type. The wiring diagram or connections are fully illustrated in Figure 4, and need not be described in connection with the description of the 15 structure of Figures 1, 2 and 3.

D indicates a transformer adapted to supply low voltage alternating current to the tube filaments. Since the particular details of the transformer do not form part of the present invention, 20 a merely diagrammatic showing is employed.

Positioned at the upper end of the tube B² is an outwardly extending housing member including the lower flat portion E having a vertical circumferential flange E¹, and an upper portion E² overlapping the flange E¹ as at E³, provided with an inclined wall E⁴. E⁵ indicates a handle whereby the entire portable unit may be moved about. Positioned within the housing member E², and conforming generally to the inclined portion E⁵, is any suitable indicating and control drum G with an inclined wall G¹. The drum G is mounted at the upper end of a shaft G² the lower end of which connects to the shaft A⁴ through the universal joint generally shown 30 as G³. This universal joint may not be necessary, but it tends to prevent strains which would throw the condenser plates out of alignment. G⁵ indicates a bearing bushing for the upper end of the shaft G², and G⁶ a hub member for the 35 drum G, secured to the upper end of the shaft G² and resting upon the upper end of the bearing G⁵.

Means for rotating the drum include a shaft H having a knob H¹ thereupon. H² is a collar 45 which may be fixed upon the shaft and H³ an opposed collar adapted to be thrust by the spiral spring H⁴ against the edge of the drum G, whereby it is clamped between the two collars. When it is so clamped, rotation of the knob H¹ serves to 50 rotate the drum and thus actuate the condensers A³.

H¹⁰ diagrammatically indicates a variable resistance adapted to be employed as a volume control and adapted to be actuated for example by 55 the knob H¹². This can be connected so as to shunt the grid circuit of the first tube shown in Figure 4.

H¹⁵ indicates any suitable switch for turning the device on and off. It will be understood that 60 the switch H¹⁵ opens the circuit both in the unit enclosed within the movable member and in the relatively fixed housing, thus controlling the entire set.

The drum is provided with a scale G¹⁰ or may 65 be provided with two complete scales at opposite sides thereof, these scales being visible for example through one or more apertures G¹¹ in the inclined portion E⁴ of the upper housing. When 70 two such apertures are used, they are preferably at opposite sides of the wall E⁴.

C¹⁰ indicates a housing or container the lower edge of which rests upon the base A, the upper portion inwardly extending until, as at C¹¹, it approaches the tube B². It is exteriorly screw threaded as at C¹² to receive threads C¹³ upon 75

a securing or closure member C¹⁴ the upper edge of which is in close sliding engagement, as at C¹⁵, with the exterior of the tube B². It will be understood that the two members above described may be upwardly moved as a unit, in 5 order to give access to the interior of the housing. The housing so formed is shown as round in cross-section. It will be realized, however, that the particular form herein shown is optional and mainly for the purpose of obtaining an ornamental appearance and a very wide range of forms of container may be used. 10

Referring to the semi-portable unit or housing shown at the right hand of Figure 1, L indicates any suitable box or housing with which 15 is associated the cover L¹ and the handles L², and the loud speaker L³. As herein shown the box is made portable, although, because of its weight and size, it is not so readily portable as the 20 portable unit proper.

If desired, it may be located in a cabinet or under a table, or in a closet or anywhere else where it will be out of the way. If, as may be the case, a loud speaker is associated with it, or even within it, it will of course have to be 25 positioned in such location as to permit the loud speaker to be heard by the operator or listeners.

Figure 4 represents a wiring diagram of the radio frequency amplifier and detector contained in the portable unit shown in Figures 1 to 3. 30 The three radio frequency tubes are indicated as L. The transformers C¹ are employed for coupling the tubes together. The circuit is of the conventional neutralized tuned radio frequency type. I¹ is the detector tube. 35

D is a transformer with two secondary windings D¹ and D². The winding D¹ supplies the filament current for the tubes I, and the winding D² the filament current for the tube I¹. D³ is the primary coil of the transformer D. 40

The volume control is shown in Figure 4 at H¹⁰, and may consist of a variable resistance shunted across the grid circuit of the first tube to which the antenna is connected. Other volume control means may be employed if desired. I⁴ is a 45 jack located on the portable unit, to which all the connections from the radio frequency and detector portion of the set are brought. I⁵ is a cable terminating at one end in a plug I⁶ suitable for insertion in the jack I⁴. On the other end of the cable I⁵ is a plug I⁷ suitable for insertion in a jack I⁸ located on the semi-portable unit, shown at the right of Figure 1.

Referring to Figure 5, the fixed or semi-portable unit contains three audio amplifying tubes 55 K, and a rectifier tube K¹. A resistance coupled amplifier is here shown, but it will be of course understood that other forms of audio amplifier may be employed. K² is a transformer having one primary coil K³ and one high voltage secondary winding K⁴. The filament heater winding K⁵ supplies the filament current to the rectifier tube K¹. 60

These windings are connected through the tube K¹ to a filter circuit K⁸ which cooperates with 65 the transformer K² and the tube K¹ to form a B supply unit for both the portable and semi-portable portions of the set. K⁷ is a secondary winding on the transformer K² which supplies the filament current of the audio power tube K. The 70 windings K⁸ and K⁹ supply filament current to the two preceding tubes. K¹⁰ is a binding post on the semi-portable unit to which the antenna is connected. K¹¹ is a similar binding post to which a ground connection is made. K¹² are 75

leads with a plug attached suitable for plugging into a lighting fixture or connection.

It will be seen that the primary coil K^3 of the transformer K^2 and the primary coil D^3 of the transformer D are connected in parallel. One side of the line K^{12} is connected to one side of the parallel transformer primaries. The other side of the line K^{12} is connected to the other side of the parallel primaries through the switch H located with the rest of the controls in the portable unit. When the switch H^{15} is opened the current supply to the transformer D and the transformer K^2 is cut off simultaneously. The switch H^{15} is therefore adapted to start and stop the complete set. The same effect can be secured by connecting the primary D^3 and the primary K^3 in series and in series with the switch H^{15} . This will however make necessary the design of the primaries D^3 and K^3 to supply different amounts of energy with the same primary current.

Referring to the wiring connections between the two units, it will be seen that the wire I^{10} connects to the grid of the tube I at one end and extends to the jack I^4 , where it is engaged by a proper terminal on the plug I^6 and, through the cable I^5 with the plug I^7 . This is plugged into the jack I^8 on the semi-portable unit, the proper terminal of which is connected by a wire to the binding post K^{10} to which the antenna is attached. The circuit of the wire I^{11} extends, similarly, through the jacks and plugs and the cable I^5 , to the semi-portable unit where it connects to a point of proper potential on the B filter circuit K^6 , whereby the B energy for the tubes I is supplied from the transformer and filter system K^2 K^6 in the semi-portable unit. The circuit of the wire I^{12} also extends, through the jacks, plugs and cable I^5 , to the grid of the first audio-tube K . It will be seen that in this way all of the leads to the portable unit connect through one cable I^5 , which can be detached either from the portable or the semi-portable unit or both, by means of the plugs and jacks I^4 , I^6 , I^7 , I^8 .

The connection I^{12} which carries the output current from the detector tube I^1 to the first audio amplifying tube K is to some degree sensitive to an alternating current field. It may therefore be necessary in some cases to shield this connection particularly with respect to the alternating current leads I^{13} I^{14} . This can be done conveniently by enclosing the lead I^{12} in a metal sheathing, this metal sheathing being connected to the ground and constituting the conductor I^{15} . I have however secured satisfactory hum-free operation without employing this sheathing.

If a wire I^{15} connected to the ground is run through the cable the capacitative field around the wires I^{13} and I^{14} is considerably reduced. Twisting the wires I^{13} and I^{14} so that the wire I^{12} does not link with them prevents magnetic coupling. If further shielding is desired the ground wire I^{15} may be made in the form of a braided wire tube and the wire I^{12} passed through the center of it. This will completely shield it from the action of the wires I^{13} and I^{14} . It has been found by test that no detrimental influence results from passing the wire I^{10} connected to the antenna K^{10} through the cable, with the possible exception of a slight loss in antenna energy which is not especially objectionable. I^{16} is a condenser one side of which is connected to the wire I^{12} and the other side to ground. This by-passes any radio frequency energy present in the plate cir-

cuit of the tube I^1 thus largely preventing it from passing to the cable I^5 .

It will be realized that whereas I have described and shown a practical and operative device, nevertheless many changes may be made in the size, shape, number and disposition of parts without departing from the spirit of my invention and in details of wiring, circuit and arrangement of parts, and even in distribution of the various parts between the two units. It will be therefore realized that I wish my description and drawings to be taken as in a broad sense illustrative and diagrammatic, rather than as limiting me to the particular description and showing herein contained.

For example where in the claims the housing is described as being located adjacent the floor that I wish such terms including a housing actually resting on the floor and also a housing spaced above the floor, for example positioned upon legs or intermediate supports, provided that such housing, and the parts therein, are still near enough the floor to maintain the center of gravity of the set sufficiently low to maintain a high degree of stability.

I claim:

1. A remote control radio receiver comprising a central unit and a separate control unit connected together electrically by a multi-conductor cable, a variable reactance tuning circuit and a thermionic tube in said control unit, a sound reproducer and alternating current supply means in said central unit, a step-down transformer in said control unit for supplying filament current to said thermionic tube, and a pair of conductors in said cable carrying alternating current to said transformer at a voltage higher than the voltage supplied to said tube.

2. A remote control radio receiver comprising a central unit and a separate control unit connected together electrically by a multi-conductor cable, a variable reactance tuning circuit and a thermionic tube in said control unit, a sound reproducer and alternating current supply means in said central unit, a step-down transformer in said control unit for supplying filament current to said thermionic tube, a pair of conductors in said cable carrying alternating current to said transformer at a voltage higher than the voltage supplied to said tube, and a switch in said control unit for turning off said alternating current.

3. A radio receiving set comprising two relatively movable assemblies, thermionic tube means for amplifying and detecting signal current and, tuning mechanism in one assembly, and one or more audio frequency tubes in the other assembly, a single flexible cable extending to the first said assembly, said cable including a pair of alternating current power wires for furnishing filament power to said thermionic tube means and a conductor for conveying amplified detected currents from the first said assembly to the assembly containing one or more audio frequency tubes and a ground conductor and an antenna conductor, means associated with the last said assembly for connecting the ground conductor and antenna conductor to an external ground and to an external antenna respectively, and means to prevent amplified radio frequency currents from entering upon any conductor of said cable.

4. A radio receiving set comprising two relatively movable assemblies, tuning mechanism and thermionic tube means for amplifying and detecting signal current in one assembly, and one or more audio frequency thermionic tubes in the

other assembly, a single flexible cable extending to the assembly containing tuning mechanism, said cable including a conductor constituting part of an untuned circuit carrying alternating signal currents, an antenna conductor, a conductor carrying detected current, and other conductors carrying alternating power current included within the same cable, and means associated with the assembly having one or more 10 audio frequency thermionic tubes for connecting said antenna conductor to an external antenna.

5. A radio receiving set comprising two relatively movable assemblies, tuning mechanism and radio frequency amplifying and detector thermionic tubes in one assembly, and one or more 15 audio frequency thermionic tubes in the other assembly, a single flexible cable extending to the assembly containing tuning mechanism, said cable including a conductor constituting part of 20 an untuned circuit carrying alternating radio frequency signal currents and means to isolate all of the conductors of said cable from tuned or amplified radio frequency currents.

6. A radio receiving equipment consisting of 25 two relatively portable housings connected together by a single flexible cable of sufficient length to permit one of said housings to be moved from place to place about a room, conductors carrying alternating power current in said cable, 30 an antenna conductor extending into the stationary housing and thence through said cable to the portable housing and forming a part of a radio frequency circuit, radio frequency amplifying and detecting means in the portable housing, means 35 to prevent amplified radio frequency currents from entering upon any of the conductors of said cable, whereby feed-back to said radio frequency antenna circuit is prevented in the cable, and amplifying means in the other housing.

40 7. A radio receiving equipment comprising two containers, one of which is readily portable and contains tuning, amplifying and frequency changing means, a single cable having a plurality of conductors connecting said tuning, amplifying and frequency changing means in said 45 portable container with the other said container, a conductor in said cable carrying radio frequency currents, an external antenna connected to last said conductor at said other container, 50 a second conductor in said cable carrying audio frequency currents produced by the passage of said radio frequency currents through the said tuning, amplifying and frequency changing means in said portable container, means excluding any objectionable amount of said radio frequency currents from said conductor carrying audio frequency currents, means for excluding any amplified radio frequency currents from any 55 said conductor in said cable to prevent feed-back effects, and amplifying means in the other container.

65 8. A radio receiving equipment comprising two or more associated containers, one of said containers being readily portable and constituting a housing for radio frequency tuning mechanism and for radio frequency amplifying devices, said container being electrically connected with the other parts of the radio receiver by a single cable, 70 one conductor of said cable carrying radio frequency signal current to be amplified and tuned, another conductor of said cable carrying amplified signal currents at different frequencies from that of the first mentioned conductor of the 75 cable, other conductors of said cable carrying al-

ternating power current, means to prevent signal currents of like frequency but at different degrees of amplification from simultaneously entering the conductors of said cable, amplifying means in the other container, and an external 5 antenna connected to the first said conductor of the cable at said other container.

9. A radio receiving set comprising two relatively movable assemblies, one or more radio frequency tubes, tuning mechanism and a detector 10 tube in one assembly, and one or more audio frequency tubes in the other assembly, a single flexible cable extending to the assembly containing one or more radio frequency tubes and tuning mechanism, said cable including a pair of alternating current power wires for furnishing filament power to said radio frequency tube or tubes, and a conductor for conveying amplified currents of reduced frequency from the assembly containing one or more radio frequency tubes to 20 the assembly containing one or more audio frequency tubes, and a ground conductor and an antenna conductor, means to prevent amplified radio currents of the frequency of the antenna currents from entering upon any conductor of 25 said cable, an external antenna connected to the antenna conductor and an external ground connected to the ground conductor at the assembly containing one or more audio frequency tubes.

10. A radio receiving set comprising a relatively 30 movable assembly and an assembly adapted to have a relatively fixed location, tuning mechanism and one or more thermionic tubes including a frequency changing device in the relatively movable assembly, and one or more audio frequency 35 tubes in the relatively fixed assembly, a single flexible cable extending to the relatively movable assembly, said cable including a pair of alternating current power wires for furnishing filament power to said tube or tubes in the relatively 40 movable assembly and a conductor for conveying amplified currents of reduced frequency from the relatively movable assembly to the relatively fixed assembly, and a ground conductor and an antenna conductor, means to prevent 45 amplified radio currents of the frequency of the antenna currents from entering upon any conductor of said cable, and means on the relatively fixed assembly for connecting said ground conductor and said antenna conductor to an external ground and to an external conductor, respectively.

11. A radio receiving equipment consisting of two relatively portable housings connected together by a single flexible cable of sufficient length 55 to permit one of said housings to be moved from place to place about a room, a floor engaging member at one end of last said housing, control and indicating means at the other end of last said housing, said cable being connected to last 60 said housing adjacent said floor engaging member, and an antenna conductor extending into the stationary housing and thence through said cable to the portable housing and forming part of a radio frequency circuit, radio frequency amplifying means, and a detector in the portable housing, means to prevent amplified radio currents of the same frequency as the antenna from entering upon any of the conductors of said 65 cable, whereby feed-back to the radio frequency 70 antenna circuit is prevented in the cable, and amplifying means in the other housing.

12. A radio receiving equipment comprising two containers, one of which is readily portable and contains tuning, amplifying and frequency chang- 75

- ing means and is provided with a floor engaging member at its lower end and control and indicating means at its other end, a single cable attached to said portable container adjacent said floor engaging member having a plurality of conductors connecting said tuning, amplifying and frequency changing means in said portable container with the other said container, a conductor in said cable carrying currents of carrier wave frequency, a second conductor in said cable carrying currents of substantially lower frequency produced by the passage of said currents of carrier wave frequency through the said tuning, amplifying and frequency changing means in said portable container, other conductors in said cable carrying alternating power current, means for excluding any objectionable amount of currents of carrier wave frequency from said conductor carrying currents of substantially lower frequency, means for excluding any amplified currents of carrier wave frequency from any conductor in said cable to prevent feed-back effects, amplifying means in the other container and means at said other container for attaching an external antenna to the first said conductor of said cable.
13. A radio receiving equipment comprising two containers, one of which is readily portable and contains tuning, amplifying and frequency changing means, a single cable having a plurality of conductors connecting said tuning, amplifying and frequency changing means in said portable container with the other said container, a conductor in said cable carrying currents of carrier wave frequency, a second conductor in said cable carrying currents of substantially lower frequency produced by the passage of said currents of carrier wave frequency through the said tuning, amplifying and frequency changing means in said portable container, means for excluding any objectionable amount of currents of carrier wave frequency from said conductor carrying currents of substantially lower frequency, amplifying means in the other container, and means on said other container for connecting said conductor carrying currents of carrier wave frequency to an external antenna.
14. A radio receiving equipment comprising two containers, one of which is readily portable and contains tuning, amplifying and frequency changing means, a single cable having a plurality of conductors connecting said tuning, amplifying and frequency changing means in said portable container with the other said container, a conductor in said cable carrying currents of carrier wave frequency, a second conductor in said cable carrying currents of substantially lower frequency produced by the passage of said currents of carrier wave frequency through the said tuning, amplifying and frequency changing means in said portable container, other conductors in said cable carrying alternating power current, means for excluding any currents of carrier wave frequency at objectionably high voltage from the conductor carrying currents of substantially lower frequency, amplifying means in the other container, and means on said other container for connecting the conductor carrying currents of carrier wave frequency to an external antenna.
15. A radio receiving equipment comprising two containers, one of which is readily portable and contains the tuning mechanism of said receiving equipment, a single cable including all of the conductors connecting said portable container and tuning means with the other said container, one of said conductors in said cable carrying
- a radio signal of carrier frequency, a second of said conductors in said cable carrying a signal of lower frequency which is produced by the passage of said first signal through the apparatus and tuning means in said portable container, means for excluding any currents of carrier wave frequency at objectionably high voltage from said conductor carrying the lower frequency, amplifying means in the other container and means on said other container for attaching the cable carrying the radio signal of carrier frequency to an external antenna.
16. A radio receiving equipment comprising two or more associated containers, one of said containers being readily portable and adapted to rest upon the floor, said container consisting of a housing for radio frequency tuning mechanism and for radio frequency amplifying devices, controls for said mechanism and devices located at the upper end of said housing, said housing being electrically connected with the other parts of the radio receiver by a single cable, one conductor of said cable carrying radio frequency signal current to be amplified and tuned, another conductor of said cable carrying amplified currents at different frequencies from that of the first mentioned conductor of the cable, other conductors of said cable carrying alternating power current, means to prevent currents of like frequency but at different degrees of amplification from simultaneously entering the conductors of said cable, amplifying means in the other container, and an external antenna connected to the conductor carrying radio frequency signal current at said other container.
17. A radio receiving equipment comprising two containers, one of said containers being readily portable and adapted to rest upon the floor, said container providing a housing for tuning, amplifying and frequency changing means, controls for said tuning, amplifying and frequency changing means located at the upper end of said housing, a single cable having a plurality of conductors connecting said tuning, amplifying and frequency changing means in said portable container with the other said container, a conductor in said cable carrying currents of carrier wave frequency, a second conductor in said cable carrying currents of substantially lower frequency produced by the passage of said currents of carrier wave frequency through the said tuning, amplifying and frequency changing means in said portable container, means for excluding any objectionable amount of currents of carrier wave frequency from said conductor carrying currents of substantially lower frequency, and amplifying means in the other container.
18. A radio receiving equipment consisting of two housings connected together by a single flexible cable, an antenna conductor extending from one housing and thence through said cable to the other housing and forming part of a radio frequency circuit, other conductors extending through said cable carrying alternating power current, radio frequency amplifying and detecting means in the last said housing, means to prevent amplified radio currents of the same frequency as the antenna from entering upon any of the conductors of said cable, whereby feed-back to the radio frequency antenna circuit is prevented in the cable, amplifying means in the first said housing, and an external antenna connected to the antenna conductor at the first said housing.
